J. R. ANDERSON

PLANE

Filed Jan. 20, 1922

FIG. 1

FIG. 2

FIG. 3

Inventor:

John R. Anderson
By: Wm. O. Bell, Atty.

UNITED STATES PATENT OFFICE.

JOHN R. ANDERSON, OF MOLINE, ILLINOIS.

PLANE.

Application filed January 20, 1922. Serial No. 530,517.

To all whom it may concern:

Be it known that I, JOHN R. ANDERSON, a citizen of the United States, residing at Moline, in the county of Rock Island and 5 State of Illinois, have invented certain new and useful Improvements in Planes, of which the following is a specification.

This invention relates to planes used in joinery and has for its principal object to 10 provide a simple structure including a minimum number of parts, all of which are adapted for quantity production.

Another object of the invention is to provide a simple plane stock that can be advantageously made of pressed metal.

Another object of the invention is to enable the blade to be easily and quickly secured in place in a manner permitting ready adjustment.

20 Further objects of the invention will become apparent as the description is read in connection with the accompanying drawing showing a selected embodiment of the invention, and in which

25 Fig. 1 is a longitudinal central sectional view; and

Figs. 2 and 3 are transverse sectional views on the line 2—2 and 3—3 respectively of Fig. 1.

30 The stock 10 of the plane is preferably made of sheet metal in the form of a channel having a smooth flat face 11 on the bottom of the web portion 12 and the curved upper edges 13 on the side flanges 14. The flanges 35 should be higher at the front end of the stock as indicated in order to protect the fingers from the shavings that might otherwise veer off to the side. The rear portions of the flanges are preferably low, substantially as 40 indicated, in order to let the palm of the hand come against the smooth curved surface of the locking lever 15 during the movement of the plane in use.

The web 12 is provided with a transverse 45 slot 16 of sufficient width to leave a proper aperture for shavings in front of the bit 28. To the rear of the slot and some distance above the web depending on the inclination of the bit, I provide an abutment 17 here 50 shown as a rivet passing through the flanges 14 and having its heads 15 countersunk therein.

The bit is preferably held in place against the rear wall of the slot 16 and the abutment 55 17 by a lever 15 which is fulcrumed so as to slightly pass "center" in moving from

locked to unlocked position. As shown, the lever has the short arm 18 extending forwardly and upwardly from a notch 19, for receiving the fulcrum 20, and a curved long 60 arm 21 bent as indicated at 22 and terminating in a strut 23 having a flat end 24 to rest against the upper surface of the web 12. The fulcrum is here shown as formed by a plate 25 secured to the web by a rivet 26 65 and having one end bent upwardly at 20 and the other end beveled to form an inclined support 27 for the lower end of the bit 28. The lever 15 is substantially channel shape 70 in cross section and at the bend takes a somewhat spherical form so as to present a smooth surface to the palm of the hand.

When it is desired to insert the blade the lever 15 is raised to the dotted line position shown in Fig. 1, the blade inserted from beneath to approximately the dotted line position shown in Fig. 1, the stock and blade then rested on a flat surface and the lever moved to the solid line position shown in Fig. 1. This last movement of the lever 80 bends the bit slightly as indicated and the short arm 18 passes slightly above the point on the blade nearest to the upper end of the fulcrum 20, or in other words, passes center 85 so that the force of the blade in trying to straighten tends to rotate the lever clockwise, which is prevented by the end 24 of the long arm of the lever coming in contact with the web 12 as shown. To remove the bit, the lever is thrown to the dotted line 90 position shown in Fig. 1, and the bit drawn out through the slot 16. To adjust the bit for a deeper cut it may be tapped on the upper end with a mallet or the like and to adjust it to make the edge parallel with the 95 face 11 it may be tapped on the proper side edge in a well-known manner.

This construction results in an extremely strong tool which can be made in quantity at a very low cost. The stock may be easily 100 produced from pressed metal with the face 11 practically plane. The abutment 17 and fulcrum 20 can both be assembled by machine operation. The bit 28 can be made, as usual, from bar stock, and the lever 15 105 can be made by either casting, drop-forging, or pressing. The three parts constituting the tool can be shipped in knocked down condition and assembled with the use of unskilled labor.

I am aware that changes may be made in the form, construction and arrangement of

the invention, as set forth in the selected embodiment herein, without departing from the scope or sacrificing any of its material advantages, and I therefore reserve the right to make all such changes as fairly fall within the scope of the following claims:

I claim:

1. In a plane, the combination of a stock 10 having a slot for a bit, an abutment on said stock above and to the rear of said slot, a bit extending through said slot and beneath said abutment, and a lever fulcrumed on said stock to the rear of said abutment, and 15 bearing against said bit to bind the latter against said abutment and said stock.
2. In a plane, a stock having a slot therein for a bit, an abutment on said stock above and to the rear of said slot, a bit extending 20 through said slot and beneath said abutment, a fulcrum on said stock to the rear of said abutment, and a lever engaged with said fulcrum and engaging said bit with one end and said stock with the other.
3. In a plane, the combination of a channel-shaped stock including a web, upwardly 25

extending flanges spaced apart, and a transverse abutment between said flanges, said web having a transverse slot for a bit, a bit extending beneath said abutment and 30 through said slot, and a lever fulcrumed behind said bit and adapted to bind said bit against said abutment and said web.

4. In a plane, a channel shaped stock comprising a web having a plane face, flanges 35 extending upwardly from said web, and an abutment connecting said flanges above said web, a fulcrum secured to said web, a bit passing through said web and beneath said abutment, and a bent lever on said fulcrum 40 and having a short arm engaging said bit and a long arm engaging said stock.

5. In a plane, a stock having a slot therein for a bit, an abutment on said stock, a fulcrum on said stock, a bit passing through 45 said slot and beneath said abutment, a lever pivoted on said fulcrum having a short arm for engagement with said bit and a long arm for engagement with said stock, said long arm being bent to form a curved seat 50 for the hand.

JOHN R. ANDERSON.
